UNITED STATES PATENT OFFICE.

ALFRED A. R. BERGER, OF BROOKLYN, NEW YORK.

SHEARING DEVICE.

Application filed January 5, 1922. Serial No. 527,109.

To all whom it may concern:

Be it known that I, ALFRED A. R. BERGER, a citizen of the United States, and a resident of the borough of Brooklyn, county of 5 Kings, city and State of New York, have invented certain new and useful Improvements in Shearing Devices, of which the following is a specification.

My invention relates to the class of shearing devices set forth in concurrent application Serial No. 450,440, filed March 7, 1921, my present improvements being likewise designed more especially for shears used in detaching coupons from interest bearing 10 documents, and for analogous purposes, where rectangular severance is required or desirable,—the object being to provide means whereby a single cutting operation will suffice to detach a rectangular coupon, section, certificate, or other incidental sectional part of a bond, or other commercial paper, from the rest of the sheet, thereby saving 15 time and labor, particularly where the necessary clippings are numerous, as after the accruing of interest on bonds held in quantity in safety vaults, etc. Such coupons or adjunctive parts of a bond or document of the character designated being almost invariably of oblong rectangular outline, an 20 ordinary pair of scissors, or shears, has to be used twice for each section detached, also involving the turning of the document to effect one cut at right angles to the other, the resultant inconvenience, and the time 25 lost in the operations, being disadvantageous in proportion to the number of documents to be thus manipulated.

My main object in the present case is to simplify and cheapen the construction of 30 shears of this class and facilitate manipulation thereof, while obviating the aforesaid difficulties heretofore encountered in the prior state of the art; and to this end my invention consists primarily and essentially 35 in the specific construction, combination, and arrangement of parts and appurtenances herein described and claimed,—distinctive features relating to the means for mounting and actuating the pivotally supported 40 transverse cutter blade, and other incidental and adjunctive details hereinafter clearly designated.

In the accompanying drawings,

Fig. 1, is a top view of my improved 45 shearing implement;

Fig. 2, is a side elevation thereof, with the parts shown in normal relationship;

Fig. 3, is a front end view of my improved shearing device, with the transverse 50 blades closed;

Fig. 4, is an elevation of the front end of the device, showing the transverse cutter blades apart and in normal co-relationship;

Fig. 5, is a detail view of shear handles which may be incorporated with my main 55 longitudinal cutting blades.

I have herein, for convenience of description, designated the main or larger cutting blades a, a' , as the longitudinal blades, they being under ordinary conditions of greater 60 length than the end or transverse blades b, b' , which latter are presumably, although not necessarily, shorter than the aforesaid longitudinal blades a, a' , for the reason that coupons, detachable certificates, tickets, and 65 analogous parts to be severed from a common sheet are usually of elongate rectangular configuration, and hence the longitudinal cutting blades a, a' , are provided for the severance of the longitudinal boundaries of 70 such detachable sections, and the transverse cutting blades b, b' , for the severance of the end or cross extension boundaries of such 75 individual sections, of a unitary document or sheet of the character designated. 80

The inner compound blades a, b , are preferably of integral construction, because their cutting edges may be ground true and sharpened with facility when unattached to the other or outer conjunctive blades a', b' ,—the latter being separable, the one from the other, as otherwise it would be practically impossible in a commercial sense to finish their cutting edges with accuracy at their angle of conjunction. That is to say, 85 that while it is comparatively easy to sharpen the outer edges of a rectangle, it is very difficult to sharpen the inner edges of a rectangular structure, especially at the apex of the angle. Therefore, while it is 90 desirable to make the inner unitary rectangular blades a, b , in a single piece, the pivotally connected outer blades a', b' , are preferably, in fact necessarily, made separable, and operatively coupled together at their 95 100 conjunctive ends by detachable means, substantially as hereinafter more fully set forth.

The basic extremities of the longitudinal blades a, a' , are pivotally connected by a fulcrum bolt c , and nut c' , or equivalent 110

mechanical expedient, and a spring washer a^2 , may be interposed between the nut c' , and the adjacent side of the blade to afford suitable frictional tension and resistance, 5 and insure accurate alignment of the cutting edges as related to each other.

The longitudinal blades a , a' , are normally held open with their cutting edges apart to a prescribed degree by the resiliency of a bow spring s , acting in conjunction with a stop or fixed gauge g , Fig. 2. In the specific construction shown by way of exemplification in the drawings the said bow spring s , is mounted medially on the 15 head c^x , of the fulcrum bolt c , and the otherwise free extremities of said spring rest in holes formed for the purpose in studs s' , s' , affixed respectively to the longitudinal 20 blades a , a' ; and the gauge g , is affixed to one of said blades and protrudes into a concentric slot g^2 , formed for the purpose in the other of said longitudinal blades, as shown particularly in Fig. 2,—the end walls of said concentric slot g^2 , acting as stops to 25 limit the movement of said blades a , a' , as related to each other, in either direction. By this or equivalent means the longitudinal blades a , a' , are operatively united to function as ordinary shears; and their 30 shanks a^{12} , a'' , at the rear of the fulcrum c , may be provided with any suitable extensions in the form of handles or lever arms adapted to facilitate manipulation in accordance with the requirements of special 35 use, and the power requisite to effect the severance of the sheet sections involved. Thus, in Fig. 5, I show detached handles h , h , which may be screwed or riveted to the shanks a^x , a'' , of said blades in a manner 40 well known in the art.

The outer longitudinal blade a' , is formed at its outer extremity with a rigidly attached bearing block a^3 , forming the support for the fulcrum a^4 , on which the transverse rockable blade b' , is pivotally mounted. In the construction shown in the drawings, this fulcrum a^4 , consists of a screw, the head a^{41} , of which retains said rockable blade b' , in position on the end of the longitudinal blade a' , a tension washer b^2 , being 45 by preference interposed between said head a^{41} , and the said rockable blade b' , as indicated more particularly in Figs. 2, 3 and 4.

A retractile spring r , attached to the rear 50 portion of the rocker blade b' , and to the bearing block a^3 , tends constantly to hold said rocker blade b' , in open position with its back edge in contact with a stop a^{31} , on the said bearing block a^3 , as shown more 55 particularly in Fig. 4, of the drawings.

When the longitudinal blades a , a' , are closed to bring their cutting edges in operative relationship, the rear arm b'' , of the rockable blades b' , contacts with a trip arm 60 a^x , on the extremity of the lower inner lon-

gitudinal cutting blade a , thereby rocking said transverse blade b' , into the position shown in Fig. 3. In order to reduce frictional contact during this operation, said rear arm b'' , of the rockable blade b' , is 70 preferably provided with a contactual roller b^4 , for engagement with said trip arm a^x , on the inner longitudinal blade a .

The overlap of the rear arm b'' , of the transverse rockable blade b' , beyond the end 75 of the inner longitudinal blade a , and the edge of its transverse blade b , at the angle of juncture between the cutting edges, insures continuity and conjunction of said cutting edges, and obviates the possibility of any 80 space at the apex of the angle of severance that might otherwise impair the perfection of cut, and result in raggedness of the edges of detachment.

When ordinary shears are used in cutting 85 off coupons or like supplementary parts of bonds or documents, care must be taken to have the transverse or shorter cut even, approximately at right angles to the main or longitudinal cut, otherwise both the document and the part severed therefrom may be mutilated or disfigured more or less, and hence heretofore time and skill were requisite to attain satisfactory detachment in 90 perfect alignment with the prescribed boundaries; whereas by the use of my rectangular cutting implement correct and accurate alignment is assured at a single operation, and the time and labor involved is materially reduced.

As compared with the use of a square or straight edge for the severance of coupons, etc., my rectangular shearing device is still more advantageous, as I obviate labor and inconvenience involved in holding down of 105 the square or straight edge on the paper, placed on a flat surface, and the danger of tearing the paper in irregular manner. At best the square or straight edge, when used for the purpose, leaves a ragged, unseemly 110 edge on both document and part detached.

What I claim as my invention and desire to secure by Letters Patent is,

1. In a shearing implement of the character designated, the combination of a pair 115 of pivotally connected longitudinal blades, one of which is formed integral with a transverse cutting blade, and a rockable transverse cutting blade pivotally mounted on the end of the other longitudinal blade, 120 substantially in the manner and for the purpose described.

2. In a shearing implement of the character designated, the combination of a pair of 125 pivotally connected longitudinal blades, one of which is formed integral with a transverse cutting blade, and a rockable transverse cutting blade pivotally mounted on the end of the other longitudinal blade, a stop on the latter limiting the motion of 130

said rockable cutting blade in one direction, and a retractile spring arranged to normally hold said rockable cutting blade against said stop, substantially in the manner and for the purpose described.

3. In a shearing implement of the character designated, the combination of a pair of pivotally connected longitudinal blades, one of which is formed integral with a transverse cutting blade, and a rockable transverse cutting blade pivotally mounted on the end of the other longitudinal blade, a stop on the latter limiting the motion of said rockable cutting blade in one direction, and a retractile spring arranged to normally hold said rockable cutting blade against said stop, together with a trip arm on the first named longitudinal blade arranged to actuate said transverse rockable blade against the resistance of said retractile spring, substantially in the manner and for the purpose described.

4. In a shearing implement of the charac-

ter designated, the combination of a pair of pivotally connected longitudinal blades, one of which is formed integral with a transverse cutting blade, and a rockable transverse cutting blade pivotally mounted on the end of the other longitudinal blade, a stop on the latter limiting the motion of said rockable cutting blade in one direction, and a retractile spring arranged to normally hold said rockable cutting blade against said stop, together with a trip arm on the first named longitudinal blade arranged to 25 actuate said transverse rockable blade against the resistance of said retractile spring, and a roller on said transverse rockable blade arranged to contact with said trip arm on the first named longitudinal 30 blade, substantially in the manner and for the purpose described.

ALFRED A. R. BERGER.
